UNITED STATES PATENT OFFICE.

HEBER C. PETERS, OF NEW YORK, N. Y.

ADDING MACHINE.

Application filed September 26, 1923, Serial No. 664,899. Renewed July 12, 1927.

The present invention while applicable to calculating machines of any character which are operated by rocking a lever or handle, is especially adapted for use in connection with adding or calculating machines of that type which I have fully illustrated and described in my application filed November 29, 1916, Serial Number 133,846, issued August 2, 1921, Patent Number 1,386,021.

As is well known to those familiar with the art, in calculating machines operated by rocking a lever or handle, a false result may be obtained or parts of the machine become jammed by departing from the prescribed method of operation. To prevent this happening it is customary to provide certain locks and interlocks which operate to compel a correct manipulation of the machine. My purpose has been to provide means whereby any false results or jamming of the machine during its operation, that can be caused by first operating only partially keys controlling certain calculating functions, before the operating handle is moved, or by operating the handle only partially before the total key or sub-total key is moved, are wholly prevented. To do this I provide means whereby the operating handle is locked against complete forward movement whenever any key controlling certain calculating functions of the machine is operated only partially before the operating handle is moved forward and whereby the total and sub-total key is locked if the handle is moved forward only partially. In the accompanying drawings this is shown particularly in connection with those keys known as number keys controlling the listing of amounts, and the key known as the correction key used for restoring to normal number keys wrongly depressed or to restore to normal other keys moved into operating position, such as the keys controlling the functions of totaling—sub-totaling—and non-adding. I do not wish to be considered, however, as limiting my invention in application only to keys controlling the above specified functions.

Further as is well known to those skilled in the art, in adding machines of the type where the rack forming a part of the accumulating and the printing functions advances on occasion one step to effect a transfer of a unit from a lower to a higher order, it is necessary whenever such a transfer has been

made that the rack be restored to its normal position by a subsequent stroke of the handle before the sum is printed in order to prevent a short total being recorded in lieu of the correct total. It is also considered desirable to separate on the printed slip by means of a spacing stroke (i. e. a stroke when no printing or adding is done by the machine) the total of the items from the last item recorded, to assist the eye to readily distinguish the total from the items. I have, therefore, provided a new and novel means for always insuring the taking of a spacing stroke after an item is recorded in the machine before the sum of the items registered in the machine can be printed.

In the drawings which form part of this specification and illustrate a preferred form of embodiment of invention I have designated the total and sub-total key TST—the non-add key NA and the correction key C as these designations are those commonly placed on machines to identify these parts. The operating handle I have designated H.

Fig. 1 illustrates a right side elevation with parts in normal position the operating handle being shown in dotted lines.

Fig. 2 is a left side elevation partly in section said figure illustrating the mechanism relating particularly to the parts controlling the operation of or composing the locking devices, the operating handle being shown in full lines.

Fig. 2^a is a view of detailed parts of the machine shown in perspective.

Fig. 3 is a left side elevation showing the position assumed by some of the parts when the operating handle is moved forward from A, its normal position, to B the position where the locking pawl becomes effective, the total key TST having been first moved partially into its operative position.

Fig. 3^a is a view of a detailed part of the total key locking mechanism shown in perspective; and Fig. 3^b is a detailed fragmentary view of certain parts.

Fig. 4 is a right side elevation of the keyboard showing the particular mechanism controlled by the number key to operate the locking pawl when any number key is depressed only partially.

Fig. 5 is a partial end elevation of the keyboard showing the bail (17) in its relation to the number key latching shutter.

Fig. 5 is a partial end elevation of the keyboard showing a number key fully de-

pressed and held in depressed position by the latching shutter (16) and another number key partially depressed causing the latching shutter (16) to depress the bail 17 and thru the mechanism provided to move the locking pawl 4 into path of stop 5.

1 is an S-shaped lever mounted to swing freely on a stud 1^a supported in the right side frame 2 of the machine. One end of the lever 1 is held against the stud 3 mounted on the key TST, by the tension of the spring 1^b. The face of this end is recessed engaging stud 3 so that any movement of the key TST in either direction will cause the contacting end of lever 1 to rise and thus cause the opposite end to be depressed (see Fig. 3). A locking pawl 4 is mounted to swing freely on a stud 4^a supported in the side frame 2, its rearward end tending to move downward under the tension of the spring 4^b, the tension of said spring being less than that of spring 1^b with the result that the rearward end of the locking pawl 4 may be raised by the lever 1. A stop pin 4^c mounted in the frame 2 acts to limit the downward movement. A pin 4^d, mounted on the rearward end of pawl 4, contacts with the forward end of lever 1. Thus when the key TST is moved in either extreme direction the rear end of lever 1 will be lifted and the forward end depressed and pawl 4 under tension of spring 4^b will move downward into the path of the projection 5, a steel block riveted on the plate 6, and thus will prevent the complete forward movement of the operating handle, permitting movement of said handle only from position A to position B as shown in Fig. 3. It is evident if the forward end of lever 1 is depressed by any other means, the pawl 4 will move into operative position.

The three armed lever 7 (Figs. 1 and 2) is mounted to swing freely on a stud 7^a supported in the right side piece 21 of the keyboard. A spring 7^b of tension sufficient to overcome tension of spring 4^b, one end of which is fastened to the forward arm of lever 7 and the other end to the lower plate of the keyboard, acts to move the forward arm of lever 7 downward, and the rearward arm upward, and the depending arm rearward. The right angled projecting lip 7^c of the depending arm bearing against the face of the bell crank 8 normally tends to limit the rearward movement of the depending arm of lever 7. The lower surface of the rearward extending arm of the lever 7 contacts with a stud 1^e riveted in the forward end of lever 1.

60 The bell crank 8 and latching pawl 9 are both mounted to swing freely on the screw stud 8^a supported in the side frame 2. Thru the movement of the connecting link 10, the bell crank 11 and the long link 12 it is evident (see Fig. 2) that whenever the key TST is moved completely forward or back-

ward the bell crank 8 will be rocked so that its forward end will move downward and the projecting lip 7^c of the three armed lever 7 will move rearward under the tension of the spring 7^b when the step portion 70 of the forward end of bell crank 8 passes the projecting lip 7^c. This serves to latch the key TST in either its forward or rearward position. Simultaneously with the latching of the key TST the rearward projecting arm of the three armed lever 7 will move upward and will contact with the stud 4^d of the pawl 4 and lift pawl 4 out of the path of block 5, thus making possible a complete forward movement of the operating 80 handle.

If the key NA be moved rearwardly, the forward end of the latching pawl 9 will be moved upward thru the link 13 and the latching point 9^a will immediately by contact with the lip 7^c cam the depending arm of lever 7 forward. This will depress the rearward extending arm of lever 7 which contacts with pin 1^e and will depress the forward extending arm of lever 1 and thus cause the pawl 4 to move into operative position where it will remain until by the continued upward movement of pawl 9 the lip 7^c passes under the latching point 9^a latching the lever NA in operative position and 95 allowing the lever 7 and also the pawl 4 to return to normal position.

100 It is evident, therefore, that any partial movement of the key TST in either direction or any partial movement of the key NA will lock the operating handle H against complete forward movement and said lock will remain effective until the key TST or the key NA is either latched in operative position or returned to normal.

If the correction key C be partially or fully depressed, the rearward end of the correction key lever 14 loosely mounted on the stud 14^a supported in the right side piece of the keyboard, will move upward 110 against the tension of the spring 14^b. Riveted in the rearward end of lever 14 is a pin 14^c which contacts with the lower edge of the forward arm of lever 7. The depression of the key C will thus cause the forward arm of lever 7 to rise and the rearward arm to be depressed which thru the means provided will move the pawl 4 into operative position to prevent a complete forward movement of the operating handle.

115 Referring to Fig. 5 the number key 15 is provided with a cam surface 15^a which contacts with the latching shutter 16 which swings said shutter to the right when the key is partially depressed and allows the 125 shutter to return to normal position when the key is fully depressed. The edge of shutter 16 contacts with the cam surface 17^a of bail 17 said bail extending across the keyboard from left to right and having a 130

cam surface 17^a contacting with the latching shutter for each row of keys. The bail 17 is supported at each end by levers 18 which are pinned to shaft 19, said shaft 5 passing thru the keyboard from left to right and having its bearings in the side pieces of the keyboard. On the right end of the shaft 19 is pinned the arm 20 extending rearwardly, the end of which contacts with 10 the pin 22^a riveted in the forward projecting arm of the lever 22. Lever 22 is pivoted near its center on the end of shaft 23 and is held in position by spring 22^b. Its rearward arm carries a pin 22^c which 15 contacts with the forward projecting arm of lever 1. Thus when a number key is partially depressed the latching shutter 16 moving to the right contacts with the cam surface 17^a causing the bail 17 to be depressed 20 and rocking the shaft 19 so that the arm 20 is lifted. This causes the forward extending arm of the lever 22 to be lifted and the rear extending arm of the lever 22 to be depressed thus permitting movement of the 25 pawl 4 into operative position as already described. The pawl 4 will remain in operative position until the number key is fully depressed when the latching shutter 16 will return to its normal position holding the 30 number key depressed, and allowing the bail 17 to rise and the arm 20 to return to normal and the pawl 4 to be moved out of the path of block 5. It will thus be seen that when any number key is depressed only 35 partially the operation of the machine is wholly prevented.

On short studs supported in the side plates of the printing section (Fig. 2) is the U-shaped piece 24 pivoted at 24^a adjusted to 40 rock freely backward and forward on occasion, the bar connecting the upright arms of U piece 24 being drawn rearward by the tension of the spring 24^b. Said bar is placed in the path of the forward extended 45 lower ends of the type bars 25 so that whenever the lower end of a type bar passes the bar of the U piece 24 if said bar is in its path said bar will be swung forward and the upper end of right arm 24^c of U piece 24 will be swung rearwardly. The mechanism is so adjusted, however, as will be described later that the end of type bar 25 will pass freely the bar of U piece 24 when 50 a type bar is rising to above the zero printing position but will engage it on its return. When 24^c is swung rearwardly by means described later, it releases the three armed lever 26 by disengaging the latch formed by the lip 26^a and projecting face 24^c (see Fig. 3) the vertical arm of 26 moving forward under tension of spring 26^b. The three armed lever 26 swings freely on 55 stud 26^a supported in side frame 2. Its vertical arm is curved forward and carries at its end a pin 26^c. Its long rearwardly

extending arm carries at its end a passby or wipe pawl 26^d which operates against tension of spring 26^e (see Fig. 3), the spring stud 26^f by contact with the edge of lever 26 limiting the movement of pawl 26^d in 70 one direction. Its left rearward extending arm has at its rearward end a right angled lip 26^g which normally latches under the projection on the edge of the arm 24^c resisting the tension of the spring 26^b. When 75 the piece 24 is rocked by the movement of the type bars 25 or by other means than the type bar to be described later, the latch formed by 24^c with the lip 26^g will be released and the pin 26^c can move forward, 80 the lip 26^g rising in front of 24^c holding 24 in its new position. If the key TST is in its normal inoperative position the pin 26^c will enter the slot 27 in the face of key 85 TST and will prevent movement of key TST in either direction. If the key TST has been moved only slightly out of normal inoperative position in either direction the pin 26^c will enter the enlarged portion of the slot 27 and by contact with one or the other of the faces 27^a will prevent the further movement of the key TST in one direction. If the key TST has been moved in 90 either direction a greater distance than that governed by the enlarged portion of the slot 27, the pin 26^c will come to rest against the edge of the key TST (see Fig. 3) the pawl will however by this time have been allowed to move into the path by depressing the forward end of lever 1, due to action of pin 3 acting on cam surface on rear end of lever 1 of block 5 locking the handle against 95 forward movement.

When during the operation of the machine shaft 28 is rocked backward and forward by the operating lever and its connection as fully described in Pat. #1,386,021, issued August 2, 1921 to H. C. Peters, the stud 29 carried on the arm 30, said arm being pinned to shaft 28, follows a path that 100 brings its lower face in contact with the wipe pawl 26^d. On the forward stroke the stud 29 passes by the pawl 26^d without affecting the position of the lever 26 but on the backward stroke the stud 29 engages the pawl 26^d depressing the rearwardly extending arm of 26 thus latching said lever by 105 engaging lip 26^g at 24^c and restoring said lever 26 to its normal inoperative position 110 shown in Fig. 2. It will thus be seen that if a number key is depressed on the keyboard that on the forward stroke of the handle the corresponding type bar will rise freely above 115 the zero printing position, the latch at 24^c and 26^c having been released by means to be described later (see lines 13 to 23 page 9). This normally allows 26^c to move forward and engage the slot 27 holding the key TST 120 against operation. On the return stroke the mechanism is so timed that the stud 29 en- 125

gages the pawl 26^d and restores the lever 26 to normal inoperative position before the extended end of the type bar 25 passes the bar of **U** piece 24 and the continued downward movement of said type bar 25 will again release the latch formed by 24^c and 26^e and again allow the pin 26^c to move forward and engage slot 27 in key TST and prevent the movement of key TST in either direction. 10 It will thus be seen that this arrangement prevents the operation of the key TST immediately after a figure of value has been recorded in the machine and until a spacing stroke has been taken i. e. a stroke during 15 which none of the type bars rise above the zero printing position.

For reasons to be made clear I have provided a means to insure that with every forward stroke of the operating handle the bar 20 of **U** piece 24 will be moved forward and the latch formed by 24^c and 26^e released, allowing pin 26^c to move forward and engage slot 27 whether a type bar passes above the zero printing position or not.

25 On **U** piece 24 is mounted a wip pawl 31 pivoted on a stud 31^a supported in the arm 24^c of **U** piece 24. The rearward end of the pawl is held downward by tension of spring 31^b this downward motion being 30 limited by the contact of the lower edge of the pawl 31 with the surface of the bar of **J** piece 24. A clearance at 31^c however allows free upward movement of the rear end of pawl 31 when required. The rear 35 end of pawl 31 carries a pin 31^d which engages a recess in the arm 32 which is mounted on and pinned to shaft 28. Above the recessed portion, the face of said arm 32 is radial with the center on which it swings.

40 It will be seen that immediately the shaft 28 starts to move with the forward stroke of the operating handle, the bar of **U** piece 24 will be swung forward by the action of arm 32 moving downward and forcing pin 45 31^d out of recess in the face of said arm 32 and that the latch formed by 26^e and 24^c will be released and pin 26^c will be free to move forward and engage slot 27 in key TST. Pin 31^d will ride on the radial surface of arm 32 and at the end of the return stroke will again enter the recessed portion of arm 32. During the return stroke the tension of spring 31^b will be overcome by the greater tension of spring 24^b.

50 It will thus be seen that any forward movement of the operating handle will lock the key TST against operation if said key is in its normal inoperative position. If key TST is moved slightly in either direction the 55 pin 26^c will engage the faces 27^a of the enlarged portion of slot 27 this enlarged portion being of such dimension that the movement of key TST when the faces 27^a can contact with pin 26^c has not yet been sufficient to affect the totaling or sub-totaling

function of the machine but said movement has been great enough to move lever 1 sufficiently to cause latch 4 to move into operative position locking the handle H against complete movement. This insures that 70 either the key TST or the operating handle H will be locked against operation if a partial movement of either key or handle is attempted before the other is moved. The distance that the operating handle can travel 75 before being arrested by the pawl 4 engaging the block 5 assures the unlatching of lever 26 and the engagement of pin 26^c with slot 27, thus locking key TST if the handle is moved slightly in advance of attempted 80 operation of the key TST.

I claim:

1. In an adding machine the combination of an operating handle—a total and sub-total key—a non-add key—a correction key— 85 rows of number keys and a single means operable by said keys for preventing the complete forward movement of said operating handle—said single means operating to block the complete forward movement of said operating handle whenever any one of the said keys is moved into operative position only partially.

2. In an adding machine the combination of an operating handle—a total and sub- 90 total key—a non-add key—a correction key—rows of number keys and a single means operable by said keys for preventing the complete forward movement of said operating handle when any of said keys is depressed only partially—said single means also operating to block the complete forward movement of said operating handle whenever the correction key is fully depressed.

3. In an adding machine the combination of an operating handle—depressible number keys and latching means for holding said number keys depressed, of means controlled by said latching means to prevent the complete forward movement of said operating 100 handle when any number key is depressed only partially.

4. In an adding machine the combination of an operating handle, a keyboard with rows of depressible number keys, a shutter for each row holding any number key in that row in its depressed position, a bail co-acting with all the shutters and means operable by said bail to prevent the complete forward movement of the operating handle when any 110 number key is depressed only partially.

5. In an adding machine the combination of a totaling means and a printing means and means controlled by the printing means for locking the totaling means against operation after an item has been printed.

6. In an adding machine the combination of a totaling means and a printing means and means controlled by the printing means for locking the totaling means against oper- 120 125 130

ation after an item has been printed—said locking means being operated by a member of said printing means when said printing means member is returning to normal position.

7. In an adding machine the combination of an operating handle—number keys—a correction key, keys controlling the operations of totaling—sub-totaling and non-adding with a single means acting to prevent the complete forward movement of the operating handle whenever any of the said keys are moved only partially into operating position, the operation of said single means being controlled by the partial movement of any one of said keys.

8. In an adding machine the combination of an operating handle, a total key, latching means to hold said key in operative position, and a pawl mounted on a stationary part of the machine, a projecting surface on a moving part of the machine moved by the operation of the operating handle and placed to co-operate with said pawl to prevent the complete movement of said operating handle, of means for moving said pawl into the path of said projection whenever the total key is moved only partially into operating position and means for removing said pawl from the path of said projection simultaneously with and by the operation of the latching means.

9. In an adding machine the combination of an operating handle, a total key, latching means to hold said key in operative position, and a pawl mounted on a stationary part of the machine, a projecting surface on a moving part of the machine moved by the operation of the operating handle and placed to co-operate with said pawl to prevent the complete movement of said operating handle, of means for moving said pawl into the path of said projection when the total key is moved only partially into operating position, and means for removing said pawl from the path of said projection by the operation of the latching means.

10. In an adding machine the combination of an operating handle, a non-add key, latching means to hold said key in operative position, and a pawl mounted on a stationary part of the machine, a projecting surface on a moving part of the machine moved by the operation of the operating handle and placed to co-operate with said pawl to prevent the complete movement of said operating handle, of means for moving said pawl into the path of said projection when the non-add key is moved only partially into operating position and means for removing said pawl from the path of said projection by the operation of the latching means.

11. In an adding machine the combination of an operating handle, a depressible number key, latching means to hold said key

in operative position, and a pawl mounted on a stationary part of the machine, a projecting surface on a moving part of the machine moved by the operation of the operating handle and placed to co-operate with said pawl to prevent the complete movement of said operating handle, of means for moving said pawl into the path of said projection when a number key is depressed only partially and means for removing said pawl from the path of said projection simultaneously with the operation of the latching means when the number key is depressed fully.

12. In an adding machine the combination of an operating handle, a number key, a latching means to hold said key in operative position, and a pawl mounted on a stationary part of the machine, a projecting surface on a moving part of the machine moved by the operation of the operating handle and placed to co-operate with said pawl to prevent the complete movement of said operating handle, of means for moving said pawl into the path of said projection when a number key is moved only partially into operating position and means for removing said pawl from the path of said projection by the operation of the latching means.

13. In an adding machine an operating handle, a key controlling the function of totaling arranged to be latched in operative position, latching means for said key, locking means to prevent the complete operation of said handle and means operated by the latching means to render the locking means inoperative.

14. In an adding machine an operating handle, a key controlling the function of sub-totaling arranged to be latched in operative position, latching means for said key, locking means to prevent the complete operation of said handle and means operated by the latching means to render the locking means inoperative.

15. In an adding machine an operating handle, a key controlling the function of non-adding arranged to be latched in operative position, latching means for said key, locking means to prevent the complete operation of said handle and means operated by the latching means to render the locking means operative.

16. In an adding machine an operating handle, a key controlling the function of totaling and sub-totaling arranged to be latched in operative position, latching means for said key, locking means to prevent the complete operation of said handle when the key is moved only partially into operative position and means operated by the latching means to render the locking means inoperative.
